LINK CHAIN FOR A BRACELET OR SIMILAR ARTICLE

Max Hartmann, Warwick, R.I., assignor to Armbrust
Chain Company, Providence, R.I., a corporation of Rhode Island

Filed Aug. 31, 1964, Ser. No. 81,525

Term of patent 14 years

(Cl. D45—4)

FIG. 1

FIG. 2

FIG. 3

FIG. 5

FIG. 1 is a front elevational view of a link chain for a bracelet or similar article showing my new design;

FIG. 2 is a top edge view thereof;

FIG. 3 is an enlarged front elevational view of one of the links per se;

FIG. 4 is a top edge view of the link shown in FIG. 3; and

FIG. 5 is an end view of the link shown in FIG. 3, the link being rotated 90° from the position shown in FIG. 3.

The instant chain and the links per se have the same appearance at their front and rear sides and at their top and bottom edges. Portions of the link chain are shown broken away to denote indeterminate length.

I claim:

The ornamental design for a link chain for a bracelet or similar article, substantially as shown and described.
